W. G. HASKELL, JR

JET REGULATOR FOR GAS COCKS

Filed July 1, 1924

Inventor
W. G. Haskell, Jr.
by Oving & Hague, Atty's.

UNITED STATES PATENT OFFICE.

WILLIS G. HASKELL, JR., OF CEDAR RAPIDS, IOWA, ASSIGNOR TO JOHNSON GAS APPLIANCE COMPANY, OF CEDAR RAPIDS, IOWA.

JET REGULATOR FOR GAS COCKS.

Application filed July 1, 1924, Serial No. 723,521.

To all whom it may concern:

Be it known that I, WILLIS G. HASKELL, Jr., a citizen of the United States, and a resident of Cedar Rapids, in the county of Linn and State of Iowa, have invented a certain new and useful Jet Regulator for Gas Cocks, of which the following is a specification.

My invention relates to that class of jet regulators for gas cocks in which a solid jet of gas passes directly through the center of the jet regulator at maximum jet velocity, and which may be instantly adjusted as to volume without changing the jet velocity, such for instance as disclosed in the patents to Johnson, No. 923,531, dated June 1, 1909 and No. 831,512, dated Sept. 18, 1906.

The object of my invention is to provide a jet regulator of simple, durable and inexpensive construction that may be formed complete of sheet metal by the use of dies and formers, and which may be readily, quickly and easily applied to and fitted in a gas cock, and when once fitted will firmly be held against accidental misplacement, and yet at all times be capable of being readily, quickly and easily adjusted to regulate the flow of gas into the mixer.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a vertical, central, sectional view of a gas cock and mixer having my improved jet regulator applied thereto as in use.

Figure 2 shows a top or plan view of a sheet metal blank from which my improved jet regulator may be formed.

Figure 3 shows an edge elevation of same to illustrate the beveled discharge end formed on the sheet metal before the blank is cut out.

Figure 4 shows a side elevation of my improved jet regulator detached.

Figure 5 shows an enlarged sectional view of a portion of a gas cock and regulator cap thereon and my improved jet regulator in position therein.

Figure 6 shows an end elevation of my improved jet regulator with the members

thereof expanded to their maximum open position; and

Figure 7 shows a similar view with the members contracted to their maximum closed position.

Referring to the accompanying drawings, I have used the reference numeral 10 to indicate generally a gas cock of ordinary construction. It is connected at one end to a gas supply pipe 11 and provided on its side opposite from the gas pipe with a hollow extension through which the gas is discharged into the mixer 12 of ordinary construction. The discharge extension of the gas cock is indicated generally by the reference numeral 13 and is screw threaded on its exterior and is formed on its interior with an annular chamber 14. Mounted on the screw threaded exterior is the regulator cap 15 of ordinary construction and having at its outer end a round discharge opening through which the jet regulator may project.

The jet regulator is formed complete of a single piece of sheet metal. In constructing the jet regulator, I preferably provide a piece of flat sheet spring metal 16 and bevel one edge thereof at 17, as shown in Figure 3. I then cut the metal with suitable dies to form the body portion 18, as shown in Figure 3, and four regulator members 19 extend from the side of the part 18 and are separated by the spaces 20, the outer ends being tapered at 21. In this connection, attention is called to the fact that the part 18 projects at 22 a short distance beyond the adjacent side edge of the regulator member 19. When the sheet metal has been thus cut out, it is rolled in a cylindrical shape, and its tapered ends 21 are rounded inwardly toward the longitudinal center of the jet regulator, as illustrated in Figure 4.

When thus completed, the device is of substantially cylindrical form and at the point where the two edges of the sheet metal come together, the resiliency of the metal holds them slightly spaced apart, forming the longitudinal slot 23, as shown in Figure 4.

In assembling the jet regulator, the operator slightly compresses the sides of the regulator, bringing the adjacent edges thereof close together, and then inserts it in the cylindrical chamber 14, and when inserted the resiliency of the metal tends to

expand and hold it on the interior of the chamber 14 in any position in which it may be placed. Then the regulator cap 15 is screwed into position, and after it has been 5 screwed part way back upon the discharge extension of the gas cock, the walls of its orifice will engage the end of the jet regulator and cause the jet regulator to move towards the gas cock, and this operation is 10 preferably continued until the regulator cap engages the adjacent shoulder of the gas cock, and when this has been done, the jet regulator has been moved to its proper position within the chamber 14, and its discharge end is in its closed position, as illustrated in Figure 7.

When it is desired to open the jet regulator, the regulator cap is unscrewed to the desired point for permitting the ends of the 20 jet regulator to expand to the desired amount. After the jet regulator has once been placed in proper position as described, then the regulator cap may be moved inwardly or outwardly to open or close the jet 25 regulator without in any way effecting the position of the jet regulator within the chamber 14 in the gas cock, because when the regulator cap is moved toward the gas cock, it will tend to contract the outer ends of the 30 jet regulator, as indicated by the arrows near the outer end of Figure 5, and when this is done, the shoulder at 22 will form a fulcrum, thus tending to expand the rear end of the jet regulator, as shown by the 35 arrows in Figure 5, at the rear of the jet regulator, and this will cause sufficient friction of the jet regulator against the inner walls of the chamber 14 to firmly hold the jet regulator against longitudinal movement 40 until the jet regulator is at its maximum closing position.

Heretofore jet regulators of this character have been made of tubular metal and formed by a sawing and grinding process, and this 45 process has been expensive and subject to considerable variation so that a relatively large proportion of the jet regulators were defective. My improved form of jet regulator, however, may be readily and easily 50 made from sheet metal by dies and formers of the ordinary kind, and when thus made, there are substantially no defective jet regulators.

With jet regulators of the kind heretofore 55 used, it has been necessary to provide a means for accurately regulating the distance to which the jet regulators are projected into the chamber of the gas cock, and hence the length of the chamber 14 had to be regulated 60 with great accuracy, and the length of the jet regulator also had to be correspondingly accurate; whereas with my improvement the chamber 14 may be made materially deeper than the length of the jet regulator, and

by having a jet regulator made of spring 65 sheet metal with one side open and a shoulder 22 midway between the ends thereof at the open side, then the jet regulator may be readily, quickly and easily assembled within the chamber 14, and each jet regulator automatically assumes its proper position within the chamber 14 without any special care or attention on the part of the operator, or without any great accuracy in the proper proportioning of the length of the chamber 75 14 relative to the length of the jet regulator.

I have, therefore, provided a device of this character that is not only much cheaper to manufacture than the ones heretofore used, but can be assembled in a gas cock readily and 80 quickly by unskilled workmen, and when once assembled will retain their proper relative positions for accurately working, and will not be effected by repeated manipulation of the regulator cap.

I claim as my invention:

1. In a device of the class described, the combination of a gas cock having a cylindrical gas discharge chamber, a hollow jet regulator mounted in said cylindrical chamber, a regulator cap adjustably mounted on the gas cock and formed with an opening, said jet regulator being formed with tapered outer ends designed to project through the opening in the regulator cap, and said parts being so arranged that when the regulator cap is moved toward the gas cock and the tapered outer ends thereof thereby moved toward each other, the rear portion of the jet regulator will be expanded or moved outwardly into firmer engagement with the interior of the gas cock.

2. In a device of the class described, the combination of a gas cock having a cylindrical gas discharge chamber, a hollow jet regulator mounted in said cylindrical chamber, a regulating cap adjustably mounted on the gas cock and formed with an opening, said jet regulator being formed of sheet metal divided longitudinally at one side and formed with a shoulder on one of its edges designed to engage the opposite edge, said jet regulator being also formed with tapered outer ends designed to project through the opening in the regulator cap, the adjacent sides of the jet regulator from said shoulder to the discharge end thereof being spaced apart such distance from each other that, when the regulator cap is moved to position for bringing together the discharge end portions of the jet regulator the said shoulder will serve as a fulcrum and the rear end of the jet regulator will be forced outwardly to frictionally engage and hold the jet regulator against longitudinal movement within the chamber.

Des Moines, Iowa, June 12, 1924.

WILLIS G. HASKELL, JR.
